(57) **CLAIM**

The ornamental design for a curved electronic gaming machine display, as shown and described.

DESCRIPTION

FIG. 1 is a perspective view of a curved electronic gaming machine display showing our new design in its environment of use;

FIG. 2 is a front elevational view of the curved electronic gaming machine display shown separately for complete disclosure;

FIG. 3 is a rear elevational view of the curved electronic gaming machine display of FIG. 2;

FIG. 4 is a left side elevational view of the curved electronic gaming machine display of FIG. 2;

FIG. 5 is a right side elevational view of the curved electronic gaming machine display of FIG. 2;

FIG. 6 is a top plan view of the curved electronic gaming machine display of FIG. 2; and,

FIG. 7 is a bottom plan view of the curved electronic gaming machine display of FIG. 2.

The broken lines on the back of the screen, in FIGS. 3 and 7, depict a portion that forms no part of the claim. The reaming broken lines illustrate environmental structure and form no part of the claim.
